UNITED STATES PATENT OFFICE

2,685,777

TRENCH ROLLER

Ralph J. Plas, Elyria, Ohio, assignor, by mesne assignments, to Blaw-Knox Company, Pittsburgh, Pa., a corporation of Delaware

Application December 5, 1950, Serial No. 199,179

7 Claims. (Cl. 61—63)

1

This invention relates to a trench roller and more particularly to a roller adapted to roll and compact material in a trench alongside a previously built road.

The principal object of the invention is the provision of a trench roller capable of operating in a trench along the side of a previously built road and effectively rolling and compacting material therein.

A further object of the invention is the provision of a trench roller in which a pair of heavy rollers are mounted at one side of the device for operation in a trench to roll and compact material therein.

A still further object of the invention is the provision of a trench roller having a pair of pneumatic tire wheels arranged for vertical adjustment and located on the opposite side of the machine from the roller thereof and adapted to ride upon the roadway.

A still further object of the invention is the provision of a trench roller incorporating an arrangement of rollers adapted to operate in a trench at the side of an existing road and including a pair of laterally spaced, vertically adjustable wheels operating on the existing road and wherein both the wheels and the rollers are steerable.

A still further object of the invention is the provision of a trench roller including tandem rollers spaced longitudinally with respect to one another for operation in a trench at the side of an existing road and serving to doubly compact and roll material in the trench with each single pass of the trench roller.

The trench roller disclosed herein comprises an improvement in the art of trench rollers in that the material rolling and compacting means in the present trench roller comprises a pair of longitudinally spaced tandem rollers, both of which are steerable and which are adapted to operate in a trench at the side of an existing road and thereby doubly compact and roll material in the trench with each passage of the trench roller thereover as compared with the heretofore known practice of operating a trench roller with a single roller in the trench.

The invention further contemplates the provision of a trench roller including the tandem of longitudinally spaced rollers for operation in a trench at the side of a roadway and a pair of pneumatically tired wheels, each of which is vertically adjustable for operation on the roadway and both of which, along with the tandem rollers, are steerable so that the device may be readily

2

maneuvered with respect to the trenching operation and particularly in following curves and whereby the main portion of the trench roller may be held on a uniformly horizontal plane regardless of the depth of the trench or the materials of the trench in which the rollers of the device are operated.

It is well known that in the widening of various paved roads and the like it is customary to excavate a trench at the side of a road and fill the trench with suitable road building materials which require rolling and compacting to form a suitable road surface, all for the purpose of widening the existing road. It is also known that it has been the custom in effecting such operations to require a minimum rolling and compacting of the materials in the trench and to this end various trench rollers have been devised to position a compacting wheel or roller in the trench while the majority of the machine traveled along the roadway. Such a machine is disclosed, for example, in Patent No. 2,197,395 and the same is provided with a triangular-shaped frame supported by the roller at one corner thereof and by two smaller wheels adapted to run on the roadway and one of the two smaller wheels being steerable and the other of the two smaller wheels being vertically adjustable. Trench rollers of this type have been used for the indicated purpose but have been found to be cumbersome in operation, difficult in maneuvering and to require the use of a multiplicity of the rollers to obtain sufficient compaction of the material in the trench if a continuously progressing road widening operation is undertaken.

The present invention provides for the positioning of two substantially larger and heavier compaction rollers in the trench, the rollers operating in tandem and at the same time provides means for supporting the remainder of the trench roller on the roadway and on a pair of vertically adjustable rubber tired wheels whereby the roller may be maintained on a uniform horizontal plane comparable with that of the roadway and whereby the rollers in the trench are desirably positioned with respect to the proper compaction of the material in the trench. Additionally the roller disclosed herein is arranged so that all of the supporting wheels or rollers, as the case may be, are steerable and the device rendered highly maneuverable.

It will be recognized by those skilled in the art that the present invention enables a single trench roller, including the tandem rollers as disclosed herein, to operate along a road widen-

ing project and doubly compact and roll the material in the trench upon a single passage of the machine.

With the foregoing and other objects in view which will appear as the description proceeds, the invention resides in the combination and arrangement of parts and in the details of construction hereinafter described and claimed, it being the intention to cover all changes and modifications of the example of the invention herein chose for purposes of the disclosure, which do not constitute departures from the spirit and scope of the invention.

The invention is illustrated in the accompanying drawing, wherein:

Figure 1 is a top plan view of the trench roller.

Figure 2 is a side elevation of the trench roller illustrating the steering control means and wheel height adjusting means.

Figure 3 is an enlarged detailed end elevation of one of the vertically adjustable wheels of the trench roller.

Figure 4 is a vertical section of one of the rollers on the trench roller and illustrates the driving means therefor in detail.

Figure 5 is an end elevation with parts broken away illustrating one of the rollers of the trench roller and one of the wheels of the trench roller in operating position.

By referring to the drawings and Figures 1 and 2 in particular it will be seen that the trench roller disclosed herein comprises a longitudinally extending rectangular frame 10 including a plurality of cross members 11-11, several of which support an engine 12 and a combination transmission and differential unit 13. A drive shaft 14 is positioned transversely of the transmission and differential unit 13 and has brake drums 15-15 and sprockets 16-16 on its outermost ends. A water tank 17 is positioned at one side of the frame 10 and the top thereof is provided with a suitable tread 18 forming a floor for the operator. An operator seat 19 is positioned above the tank 17 and faces sidewardly.

The frame 10 is supported at its four corners by a pair of rollers 20-20 located on one side thereof and by a pair of pneumatic tired wheels 21-21 on the other side thereof. Both the rollers 20-20 and the pneumatic tired wheels 21-21 are rotatably and pivotally mounted with respect to the frame 10 by means of axle and king pin constructions. The axles carrying the rollers 20-20 are indicated by the numerals 22-22, the inner ends of which are secured to elements 23 including vertically aligned and spaced orifices through which king pins 24-24 may be positioned to establish a pivotal connection with brackets 25 secured to the frame 10.

Each of the pneumatic tired wheels 21-21 is journaled on an axle 26 which is secured to a vertically movable plate 27 which in turn is reciprocally positioned in a vertical guide 28. The plate 27 may obviously be flat, as shown, T-shape in cross section or of channel shape in cross section if desired.

A hydraulic piston and cylinder assembly 29 is secured to the vertical guide 28, a piston rod 30 extending therefrom and engaging the axle 26 so that hydraulic pressure directed into the hydraulic cylinder 29 and against the piston therein as by means of a tubular conduit 31 will move the axle and hence the wheel 21 downwardly with respect to the vertical guide 28. This construction is best illustrated in Figures 2 and 3 of the drawings. By referring to Figure 3 of

the drawings it will be observed that the vertical guide 28 is provided with sidewardly extending, vertically aligned and spaced apertured elements 32 through which king pins 33 are positioned to pivot the vertical guide 28, the plate 27 and the wheel 21 to a bracket 34 which in turn is affixed to the frame 10.

By referring again to Figure 1 of the drawings it will be observed that the two pneumatic tired wheels 21-21 are located on one side of the longitudinally extending frame 10 and in oppositely disposed relation to the pair of rollers 20-20 heretofore referred to as being located on the opposite side of the frame 10. The wheels 21-21 and rollers 20-20 while being located in oppositely disposed pairs are not otherwise connected to one another with the exception of tie rods 35-35 which are provided for steering the oppositely disposed pairs of wheels and rollers 21-21 and 20-20, respectively, in a uniform manner. The tie rods 35-35 are pivotally secured at their wheel ends to sideward extensions 36-36 formed on the vertical guides 28-28 heretofore referred to and the tie rods 35-35 are pivotally secured at their opposite ends to sideward extensions 37-37 on the elements 23 which carry the axles 22-22 on which the rollers 20-20 are located.

Oppositely disposed, sideward extensions 38-38 on the elements 23 are pivotally secured to piston rods 39-39 which form part of a pair of secondary piston and cylinder assemblies 40-40. The secondary piston and cylinder assemblies 40-40 are positioned transversely of the frame 10 of the trench roller and pivoted as at 41-41 thereto. It will thus be seen that when hydraulic pressures are directed into the secondary piston and cylinder assemblies 40-40 the resulting motion will move the sideward extensions 38-38 and 37-37 of the elements 23 and thereby cause the axles 22-22 to pivot on the king pins 24-24. The tie rods will convey the same motion to the sideward extensions 36-36 secured to the vertical guides 28 and thereby convey the same steering motion to the wheels 21-21.

In Figure 2 of the drawings hydraulic control valves 42-42 are illustrated as being positioned adjacent the operator seat 19 for controlling the secondary hydraulic piston and cylinder assemblies 40-40 which are used for steering the trench roller. It will occur to those skilled in the art that a source of hydraulic pressure comprising a reservoir and a pump are provided so that suitable hydraulic pressure is available for operating the steering apparatus as well as the vertical adjustment of the wheels 21-21 heretofore referred to.

Still referring to Figure 2 of the drawings it will be seen that tubular conduits 43 and 44 connect the valves 42-42 with the secondary hydraulic piston and cylinder assemblies 40-40 and supply and return lines 45 and 46 establish communication between the control valves 42-42 and a reservoir and pump 47. Hydraulic control valves 48-48 are shown controlling the conduits 31 heretofore referred to as being connected with the hydraulic cylinders 29 on the vertical guides 28 and by means of which the wheels 21-21 are adjusted vertically. It will thus be seen that an operator on the seat 19 can readily control the trench roller both with respect to the steering of the rollers and wheels of the device and the vertical adjustment of the wheels so that the frame 10 and its various mechanisms may be carried on a horizontal plane when the rollers 20-20 are operating in the trench as illustrated in Figure 5

of the drawings or when the rollers are operating on the same level as the wheels as shown in Figure 2 of the drawings.

In order that driving motion may be conveyed from the sprockets 16-16 to the rollers 20-20, a pair of stub shafts 49-49 are journaled in bearings 50-50 on the frame 10 at the sides thereof adjacent the wheels 21-21, the stub shafts 49-49 being provided with sprockets 51-51. A chain 52 connects one of the sprockets 51 with one of the sprockets 16 heretofore referred to as being located on the drive shaft 14.

A jack shaft 53 is positioned transversely of the frame 10 journaled on bearings 54-54 and provided with sprockets 55-55 on its opposite ends. A chain 56 connects one of the sprockets 55 with the other one of the sprockets 51 and a chain 57 connects the other one of the sprockets 55 with the other one of the sprockets 16. Thus, driving motion originating in the engine 12 and conveyed through the transmission and differential unit 13 to the drive shaft 14 turns the sprockets 16-16 and hence the sprockets 51-51 by way of the chains 52, 57 and 56. The motion thus imparted the stub shafts 50 is conveyed to the rollers 20-20 by way of drive shafts 58-58 provided with double universal joints 59 and 60, the universal joints 60 being located directly over the king pins 24-24 heretofore referred to and serving to connect the drive shafts 58-58 with secondary stub shafts 61-61 which are journaled on the elements 23 and provided with pinions 62-62. The pinions 62-62 are each engaged on the periphery of ring gears 63-63 which are in turn affixed as by bolts 64 to the rollers 20-20. It will thus be seen that the trench roller is driven by motion imparted directly to the rollers 20-20 and that the manner of conveying the motion to the rollers 20-20 is such that they are able to be steered by the steering mechanism hereinbefore described and including the secondary hydraulic and piston cylinder assemblies 40-40.

By referring now to Figures 1 and 5 of the drawings it will be observed that the center point of both the rollers 20-20 and the wheels 21-21 are equally spaced with respect to the center lines of the king pins 24-24 and 33, respectively, thereby facilitating easy steering control of the trench roller. By referring to Figure 5 in particular it will be seen that this spacing occurs by reason of the intermediate positioning of the axle 26, plate 27 and vertical guide 28, which construction is not duplicated on the roller side of the trench roller.

In Figure 2 of the drawings the rollers 20-20 and the pneumatic tired wheels 21-21 are shown on a flat surface with the wheels in their lowermost position and thereby maintaining the rollers 20-20 in horizontal relation to the road surface. In Figure 5 of the drawings one of the rollers 20 is shown operating in a trench at some depth below the surface of a roadway while one of the wheels 21 is shown operating on the relatively higher surface of the roadway. The horizontal alignment of the frame 10 is maintained as the wheel 21 is in elevated position and the horizontal surface of the roller 20 is thus maintained in desired relation to the material in the trench. In Figure 5 of the drawings the surface is indicated by the letter R and the surface of the material in the trench by the letter T.

By referring again to Figure 1 of the drawings it will be seen that when the trench roller is to be operated about a curve, the rollers 20-20 as well as the wheels 21-21 may be steered in oppo-

site directions so that both ends of the trench roller conform with the radius of the curve being followed and thereby enable a perfect rolling operation to be accomplished with both rollers

5 20-20 in the trench.

It will be observed that when steering action takes place, the secondary hydraulic piston and cylinder assemblies 40 used for moving the wheels 21-21 and the rollers 20-20 pivot upon their 10 end pivots 41 in following the steering motion and the relative positioning of the sideward projections 38-38 to which the piston rods thereof are pivotally connected.

Still referring to Figure 1 of the drawings it 15 will be observed that equal driving and braking action may be imparted the rollers 20-20 as the driving action originates through the drive shaft 14 and is uniformly conveyed to the rollers 20-20 therefrom and the brake drums 15 are provided

20 on the drive shaft 14 so that equal braking action may be applied to the rollers 20-20 through the driving mechanism. This enables the trench roller to be operated under abnormal conditions, for example, on wet or slippery materials or sur-

25 faces without sideward slippage or other undesired action. In this respect it will be recognized that the pneumatic tired wheels 21-21 normally riding the road contribute greatly to maintaining the trench roller in longitudinal alignment with 30 the trench in which the rollers 20-20 are operating.

It will be understood by those skilled in the art that the frame 10, including the cross pieces 11 and the rollers 20-20 are heavily constructed 35 so that the total weight of the device as directed by the rollers 20-20 on the material in the trench is sufficient to compact the same satisfactorily and the two rollers result in double compaction and rolling of such material with a single passage 40 of the machine.

It will also be seen that the trench roller may be operated in either direction with equal ease of control and guidance as the operator seat is located at the side of the device and above the 45 trench in which the rollers 20-20 normally operate and the operator is therefore in a position to continually observe the location of the rollers 20-20 in the trench and the action resulting from their operation.

50 A further advantage of the construction will occur to those skilled in the art and the same comprises the unusually large diameter of the rollers 20-20 made possible and practical by the design and construction of the trench roller 55 and which large diameter results in uniform compacting of material being rolled rather than bunching or crowding of material before the roller as in the case of rollers of smaller diameter.

It will occur to those skilled in the art that it 60 is desirable under some conditions to provide for the wetting of the surfaces of the rollers 20-20. This is particularly true when the rollers are employed in a finishing operation in which material incorporating a bituminous binder is employed.

65 The water tank 17 is therefore provided for the purpose of supplying liquid for wetting the rollers 20-20 and which liquid may be applied in any convenient manner from the tank 17. The tank 17 also adds weight to the trench roller which is 70 desirable in the compaction of some materials.

It will thus be seen that the several objects of the invention have been met by the trench roller disclosed herein.

Having thus described my invention, what I 75 claim is:

1. In a trench roller, the combination with a frame of a pair of longitudinally spaced supporting wheels for operation on a roadway, said wheels being located on one side of said frame and vertically adjustable relative thereto, and a pair of longitudinally spaced compaction rollers located on the other side of said frame in position to travel along a lowered road surface and in fixed vertical relationship with said frame, each compaction roller being located opposite one of the wheels, each of said compaction rollers being pivotally connected to said frame so as to be steerable relative thereto, means effecting pivoting of said compaction rollers for effecting steering of the compaction rollers, means coupling said compaction rollers with the corresponding supporting wheels on the opposing side of the frame for simultaneous coupled steering of corresponding supporting wheels and compaction rollers, and power drive means for effecting movement of the trench roller over the supporting surfaces.

2. In a trench roller, the combination with a frame of a pair of longitudinally spaced supporting wheels for operation on a roadway, said wheels being located on one side of said frame and vertically adjustable relative thereto, and a pair of longitudinally spaced compaction rollers located on the other side of said frame in position to travel along a lowered road surface and in fixed vertical relationship with said frame, each compaction roller being located opposite one of the wheels, each of said compaction rollers being pivotally connected to said frame so as to be steerable relative thereto, longitudinal extensions on the pivotal connections of said compaction rollers for movement with the latter, first means connected to the pivotal connections of said rollers for effecting pivoting, steering movement of the rollers, second means coupling said compaction rollers with the corresponding supporting wheels on the other side of the frame for simultaneous coupled steering of corresponding supporting wheels and compaction rollers, and power drive means for effecting movement of the trench roller over the supporting surfaces.

3. In a trench roller, the combination with a frame of a pair of longitudinally spaced supporting wheels for operation on a roadway, said wheels being located on one side of said frame and vertically adjustable relative thereto, and a pair of longitudinally spaced compaction rollers located on the other side of said frame in position to travel along a lowered road surface and in fixed vertical relationship with said frame, each compaction roller being located opposite one of the wheels, each of said compaction rollers being pivotally connected to said frame so as to be steerable relative thereto, longitudinal extensions on the pivotal connections of said compaction rollers for movement with the latter, first means connected to the pivotal connections of said rollers for effecting pivoting, steering movement of the rollers, second means coupling said compaction rollers with the corresponding supporting wheels on the other side of the frame for simultaneously coupled steering of corresponding supporting wheels and compaction rollers, and power drive means for effecting movement of the trench roller over the supporting surfaces, said first means including separately controlled fluid pressure means connected to each of said longitudinal extensions.

4. In a trench roller, the combination with a frame of a pair of longitudinally spaced supporting wheels for operation on a roadway, said wheels

being located on one side of said frame, said frame including a pivotally mounted guide for vertically adjustably supporting each of said supporting wheels on said frame, and a pair of longitudinally spaced compaction rollers located on the other side of said frame in position to travel along a lowered road surface and in fixed vertical relationship with said frame, each compaction roller being located opposite one of the wheels and being pivotally connected to said frame so as to be steerable relative thereto, means effecting pivoting of said compaction rollers for effecting steering of the compaction rollers, means coupling each compaction roller with the guide for one of the wheels on the opposing side of the frame for simultaneously coupled steering of corresponding supporting wheels and compaction rollers, and power drive means for effecting movement of the trench roller over the supporting surfaces.

5. In a trench roller, the combination with a frame of a pair of longitudinally spaced supporting wheels for operation on a roadway, said wheels being located on one side of said frame and vertically adjustable relative thereto, and a pair of longitudinally spaced compaction rollers located on the other side of said frame in position to travel along a lowered road surface and in fixed vertical relationship with said frame, each compaction roller being located opposite one of the wheels, each of said compaction rollers being pivotally connected to said frame so as to be steerable relative thereto, means effecting pivoting of said compaction rollers for effecting steering of the compaction rollers, means coupling said compaction rollers with the corresponding supporting wheels on the opposing side of the frame for simultaneously coupled steering of corresponding support-wheels and compaction rollers, and power drive means connected to said steerable compaction rollers for effecting rotation thereof to propel the frame.

6. In a trench roller, the combination with a frame of a pair of longitudinally spaced supporting wheels for operation on a roadway, said wheels being located on one side of said frame, said frame including a pivotally mounted guide for vertically adjustably supporting each of said supporting wheels on said frame, and a pair of longitudinally spaced compaction rollers located on the other side of said frame in position to travel along a lowered road surface and in fixed vertical relationship with said frame, each compaction roller being located opposite one of the wheels and being pivotally connected to said frame so as to be steerable relative thereto, longitudinal extensions on the pivotal connections of said compaction rollers and said guides for movement therewith, first means interconnecting the longitudinal extensions of the supporting wheel guide and compaction roller at each end of the frame for simultaneous movement, and second means effecting pivoting of said compaction rollers and their extensions, and power drive means for effecting movement of the trench roller over the supporting surfaces.

7. In a trench roller, the combination with a frame of a pair of longitudinally spaced supporting wheels for operation on a roadway, said wheels being located on one side of said frame, said frame including a pivotally mounted guide for vertically adjustably supporting each of said supporting wheels on said frame, and a pair of longitudinally spaced compaction rollers located on the other side of said frame in position to

travel along a lowered road surface and in fixed vertical relationship with said frame, each compaction roller being located opposite one of the wheels and being pivotally connected to said frame so as to be steerable relative thereto, longitudinal extensions on the pivotal connections of said compaction rollers and said guides for movement therewith, first means interconnecting the longitudinal extensions of the supporting wheel guide and compaction roller at each end of the frame for simultaneous movement, and second means effecting pivoting of said compaction rollers and their extensions, and power drive means for effecting movement of the trench roller over the supporting surfaces, said second means including fluid pressure means operable to in-

dividually control the pivoting movement of the compaction rollers.
